(57) **CLAIM**

The ornamental design for a tablet keyboard case, as shown and described.

DESCRIPTION

FIG. 1 is a front perspective view of a tablet keyboard case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the tablet keyboard case in an alternate configuration thereof;

FIG. 10 is a rear perspective view showing the tablet keyboard case in an alternate configuration thereof;

FIG. 11 is an enlarged detail view of area 11 in FIG. 1 thereof; and,

FIG. 12 is an enlarged detail view of area 12 in FIG. 2. The broken lines in the drawings illustrate the portions of the tablet keyboard case, which form no part of the claimed design.

The dash-dot-dash broken lines encircling the enlarged views are for annotative purposes only and form no part of the claim thereof.

1 Claim, 12 Drawing Sheets
